UNITED STATES PATENT OFFICE.

ROBERT M. DIXON, OF EAST ORANGE, NEW JERSEY.

DESIGN FOR A GLOBE FOR LAMPS.

SPECIFICATION forming part of Design No. 34,685, dated June 25, 1901.

Application filed May 25, 1901. Serial No. 61,976. Term of patent 14 years.

To all whom it may concern:

Be it known that I, ROBERT M. DIXON, a citizen of the United States, residing at East Orange, county of Essex, State of New Jersey, have invented and produced a new, useful, and original Design for Globes for Lamps, of which the following is a specification, reference being had to the accompanying drawings, forming part hereof.

The leading feature of my design is a globe for lamps of the general form of half of an oblate sphere and having its edge projecting upwardly and inwardly, constituting a lip of a general ogee shape in cross-section.

In the accompanying drawings I have shown a globe embodying my design.

In the drawings, Figure 1 is a general per-

spective view of the globe. Fig. 2 is a transverse section thereof.

In the drawings, 1 indicates the body of the globe, which is shown as in the form of half of an oblate sphere. At the edge of the body is a lip 2 of a general ogee shape in cross-section. As will be seen, this lip extends inwardly and upwardly, being curved at 3 and 4 in opposite directions.

Having described my design, what I claim is—

The design for a globe for lamps, substantially as herein shown and described.

ROBERT M. DIXON.
